UNITED STATES PATENT OFFICE.

LOUIS WALTER HARDY, OF YELLOW SPRINGS, OHIO.

DOOR-CHECK.

SPECIFICATION forming part of Letters Patent No. 409,194, dated August 20, 1889.

Application filed April 19, 1889. Serial No. 307,805. (No model.)

To all whom it may concern:

Be it known that I, LOUIS WALTER HARDY, a citizen of the United States, residing at Yellow Springs, in the county of Greene and State of Ohio, have invented certain new and useful Improvements in Combined Door Stop and Holder; and I do hereby declare the following to be a full, clear, and exact description of the invention, such as will enable others skilled in the art to which it appertains to make and use the same.

This invention relates to improvements in door stops and holders; and it consists in the novel construction and arrangement of parts, as will be hereinafter more fully set forth.

The annexed drawings, to which reference is made, fully illustrate my invention, in which—

Figure 1 represents a side view of my device. Fig. 2 is a perspective view of the same, and Fig. 3 is also a side view showing the device holding a door at the bottom.

Referring by letter to the accompanying drawings, A designates the combined door stop and holder, consisting of the metal spring-plate, the portion *a* of which is bent at right angles to the horizontal portion *b*, and is provided with perforations *c*, whereby the holder may be secured to a wall above or below or at the side of a door. The outer end of the horizontal plate is bent rearwardly, leaving a V-shaped opening *d* and an inclined upper surface *e*, over which the edge of a door slides when the latter comes in contact with the holder. Within this V-shaped opening is arranged a rubber filling *f*, which projects from the inclined face rearwardly, as shown at *g*.

B represents a second plate, which is secured to the main plate, as at *h*, and the forward end *i* thereof is bent at right angles thereto, and by such projection provides a stop for the door.

It will be seen that when the door comes in contact with the outer end of the holder the

same slides over the inclined end, the spring 45 yielding sufficiently until the edge of the door passes the point *g*, when the spring goes back and holds the door between this point and the stop *i*. It will be further observed that this combined door stop and holder can be used 50 at the top or the bottom or at the side of the door, and it is simple in operation, durable, and at the same time cheap to manufacture.

It will be observed that I take a single plate A, bend one end at right angles, as indicated 55 at *a*, and perforate this end; also, that I bend the opposite end at an acute angle and fill the space with an elastic cushion *f*, protruding backward beyond the tip of the bent portion *e* of said acute angle; also, that I interpose 60 between said exposed portion of the cushion another plate B, which has an upturned or right-angular stop portion *i*. The door is thus held from jar or rattling, because the cushion acts to hold the door by elastic pressure 65 against the stop *i*, and said cushion serves also to prevent the door from injury or scratching the paint therefrom.

What I claim is—

As an improved article of commodity, the 70 within-described combined door stop and holder, comprising the following elements: a spring-plate *b*, having a rectangular portion *a* on one end, an acute angular portion on the opposite end, a rubber block confined in the 75 acute angular portion and protruding backward beyond the edge of the bent lip of said angular portion, whereby a door is prevented from injury when in contact with the holder, and an independent stop-plate *B*, having a 80 stop-lip *i*, as shown and described.

In testimony whereof I affix my signature in presence of two witnesses.

LOUIS WALTER HARDY.

Witnesses:

J. W. HAMILTON,
ELIZABETH HAMILTON.
